UNITED STATES PATENT OFFICE.

CHARLES KUHN, OF FRUITVALE, CALIFORNIA.

DOOR-MAT.

SPECIFICATION forming part of Letters Patent No. 625,040, dated May 16, 1899.

Application filed January 5, 1899. Serial No. 701,230. (No model.)

To all whom it may concern:

Be it known that I, CHARLES KUHN, a citizen of the United States, residing at Fruitvale, county of Alameda, State of California, have 5 invented an Improvement in Combination Door-Mats; and I hereby declare the following to be a full, clear, and exact description of the same.

My invention relates to a mat for cleaning 10 the feet.

It consists, essentially, in the combination, in a main exterior frame, of compartments, one of which is occupied by interlocked metal plates, the edges of which are presented upwardly to form a preliminary scraping or 15 cleaning device, and the other by a fibrous or other suitable mat-surface having an independent frame and adapted to be removably fixed in the other section, so that the user can 20 pass from one to the other to complete the cleaning of the feet.

In the accompanying drawings, Figure 1 is 25 a general view of my mat. Fig. 2 shows the manner of securing the removable fibrous mat. Fig. 3 is a view of a large-sized mat.

A is an exterior frame, here shown as rectangular in outline, and it may be made of any desired size to suit the character of work for which it is to be used. For small house- 30 holds or where but few people pass it may be made to conform in size to such mats as are usually used for such places. If for a public vestibule or other similar place, it may be made as much larger as required. This frame has 35 a dividing bar or rib C, which may either extend transversely, as here shown, or longitudinally from end to end for large mats, so that the two parts of the mat will lie in the line of travel of passing people. Upon one 40 side of the bar C is a grille-work of iron, (shown at D,) which is made in an interlocking pattern of any desired form, as herein shown filling the space between the sides, end, and cross-bar of this section and having the edges 45 upturned so as to stand vertically and serve as scrapers, upon which the feet may be partially cleansed, the loose dirt being rubbed off and falling through the interstices between the plates. Upon the other side of the bar C 50 the space is filled with a fibrous or other mat

for further and more perfect cleansing of the feet.

This mat may be made of cocoa fiber or other suitable or well-known material, as shown at D', and I have shown it as fixed into an elastic metal frame E, which is adapted to fit within the space included by the sides and end A and bar C of that compartment.

In order to remove and secure this mat, so that it can be taken out for cleaning and for other purposes, I have shown pins F projecting from the bar C and corresponding holes or indentations made in the peripheral metallic binding of the mat, so that this end may be held by simply engaging the pins and holes. 65 The other end is then pressed down within the sides A, the elasticity of the metallic border being sufficient to allow it to fit snugly within the frame A, and indentations G are made in one part and corresponding projections G' on the other, so that when pressed into place they act as spring-latches to hold 70 it and prevent its being removed under ordinary conditions. When it is desired to remove it, it is only necessary to compress the elastic border sufficiently to disengage the depressions and protuberances and lift this end out of the frame, when the other end will be disengaged from the holding-pins and it can 75 be removed.

The construction provides a cheap, convenient, and easily-cleaned mat of great durability.

Having thus described my invention, what I claim as new, and desire to secure by Letters 85 Patent, is—

1. A mat comprising a main exterior frame with subdividing-bar extending across it, a section of iron lattice-work with upturned edges secured in one half of the frame and a 90 fibrous mat secured in the other half and having a containing-frame sprung into engagement therewith.

2. A door-mat consisting of a circumscribing metallic frame having a transverse dividing-bar, a metallic cleansing-surface fixed in one half the space consisting of a lattice of iron strips having upturned edges as shown, a fibrous mat having an elastic metallic border secured thereto and means for removably 95 100

fixing said mat and its border into the other section of the main frame.

3. A door-mat consisting of a main peripheral frame having a transverse subdividing bar, a cleaning-surface formed of a lattice-work of metallic strips with upturned edges fixed in one half of the main frame, a fibrous mat having a surrounding elastic metallic border within which it is secured, said border

fitting within the remaining half of the main frame and pins and spring-catches by which said mat is removably secured in place.

In witness whereof I have hereunto set my hand.

CHARLES KUHN.
